SHAFT STRAIGHTENING PRESS

Walter Ernst, Mount Gilead, Ohio, assignor to
 The Hydraulic Development Corporation, Inc.,
 Wilmington, Del., a corporation of Delaware

Application October 28, 1942, Serial No. 463,720

17 Claims. (Cl. 153—52)

This invention relates to presses and, in particular, to shaft straightening presses.

Such shaft straightening presses usually comprise a reciprocable straightening ram and a table carrying two or more roller pairs for supporting the shaft to be straightened while it is being checked as to the portion or portions to be straightened. The said table usually also carries two or more supporting blocks to which the shaft is transferred following the above mentioned checking operation, and which support the shaft to be straightened during the actual straightening operation.

Presses of this type, as heretofore known, have the supporting means or stands for the rollers movable in horizontal direction but not in vertical direction, whereas the supporting blocks which hold the shaft to be straightened during the straightening operation are movable in horizontal as well as in vertical direction. The movement of the blocks in vertical direction is effected by the adjustment of wedges respectively associated with said blocks. Since, after each straightening step, the shaft has to be transferred from the blocks to the rollers for further checking, and in case a further straightening is required, has to be returned to the blocks, it is necessary, with the straightening presses as heretofore known to effect an adjustment of the wedges pertaining to the blocks after each checking operation and after each straightening step. It is obvious that such a manipulation is rather cumbersome and costly in time.

It is, therefore, an object of the present invention to provide an improved shaft straightening press which will overcome the above mentioned drawbacks.

It is another object of the invention to provide a shaft straightening press, in which the rollers supporting the shaft to be straightened during the checking of the portions to be rectified are moved in vertical direction, whereas the blocks supporting the shaft during the straightening operation need normally not be moved in vertical direction.

Still another object of the invention consists in the provision of a shaft straightening press as set forth in the preceding paragraph, in which the rollers are movable in vertical direction by hydraulic means.

It is a further object to provide a shaft straightening press in which both the rollers and the blocks for supporting the shaft during the checking and straightening operations respectively are adjustable in vertical direction to allow checking

and straightening of conical, stepped, or other irregularly shaped shafts, and in which the rollers are hydraulically movable in vertical direction.

5 It is a still further object to provide a shaft straightening press in which the rollers and the supporting blocks for supporting the shaft during the checking and straightening operations respectively are movable in vertical direction, and in which the blocks are hydraulically moved in vertical direction for transferring the shaft from the rollers to the blocks, whereas normally no vertical movement of the rollers is required.

Still another object of the invention consists in the provision of a shaft straightening press, including a hydraulic system for operating the straightening ram, and for actuating means to transfer the shaft to be straightened from the rollers supporting the shaft during the checking operation to the blocks supporting the shaft during the straightening operation, while means is associated with the hydraulic system to assure retraction of the ram when the checking operation is being effected.

20 A still further object of the invention consists in the provision of means which will prevent the shaft to be straightened from being lifted off the means normally supporting the shaft during the straightening operation, unless the straightening ram has been moved into a predetermined position.

25 It is still another object to provide a shaft straightening press in which, in case the working stroke of the straightening or press ram is accidentally initiated prior to the transfer of the work piece to the means, normally supporting the work piece during the straightening operation, the initiation of the straightening or working stroke of the straightening or press ram will automatically initiate the transfer of the work piece to the means normally supporting the work piece during the straightening operation.

30 These and other objects of the invention will appear more clearly from the following specification in connection with the accompanying drawings, in which:

35 Figure 1 is a front view of the press according to the invention.

40 Figure 2 is partially a section and partially a view along the line 2—2 of Figure 1.

45 Figure 3 is partially a section and partially a view along the line 3—3 of Figure 4.

50 Figure 4 is a section along the line 4—4 of Figure 1.

Figure 5 is a section along the line 5—5 of Figure 1.

Figure 6 diagrammatically illustrates the control circuits for the press according to the invention.

Figures 7 and 8 show a slight modification over the arrangement of Figures 1 to 5.

Structural arrangement

Referring now to the drawings in detail and to Figures 1 and 2 thereof in particular, the shaft straightening press shown therein substantially comprises a press yoke 10 and a press head 11 interconnected by means of strain rods 12 and nuts 13.

The press head 11 has mounted thereon a press cylinder 14 carrying a tank or fluid reservoir 15, which is connected by means of a conduit 16 with a variable delivery pump 17. The pump 17 may be of any conventional type, preferably of the type comprising servomotor means which, in response to a predetermined pressure in the pressure line 18, shifts automatically to substantially no delivery position.

The pressure line 18 leads to a four-way valve 19, which controls the supply of fluid to the press cylinder 14. The valve 19, which may be manually operable, is connected with the upper portion of the press cylinder 14 by means of a conduit 20, whereas the lower portion of the press cylinder 14 communicates with a conduit 21 leading to the four-way valve 19. The conduit 21 comprises a check valve 22, which may be by-passed by means of a conduit 23 with a choke 24.

The valve shaft 25, pertaining to the valve 19, has connected thereto a linkage 26 which is operable by the hand lever 27, and which has also connected thereto a lever arm 28 adapted to be engaged by flanges or collars 29, 30, of a push rod 31. The push rod 31 has adjustably mounted thereon a collar 32 and is guided in guiding means 33 connected to one of the strain rods 12. The collar 32 is adapted to be engaged by a sleeve 34 supported by the press platen 35 connected to or supported by the press ram 36.

If it is desired to bring the press ram during its retraction or upward stroke to a halt prior to the boss 37 (see Figure 6) being engaged by the ram 36, the collar 32 is so adjusted on the push rod 31 that the sleeve 34, at the end of its upward movement, engages the collar 32 and, by means of the latter, lifts the push rod 31 to such an extent that the lever arm 28 shifts the valve 19 into position for closing fluid connection between the conduit 20 and the conduit 18. Since, during the upward stroke of the press ram 36, the conduit 20 constitutes the exhaust line, it will be clear that closure of the exhaust line by the valve 19 will bring the ram 36 to a halt.

Pressure will then build up in the pilot line 38 leading to the servomotor 39 so that the servomotor 39 shifts the pump 17 to substantially neutral or no delivery position, in a manner well known to those skilled in the art.

If it is desired to bring the ram 36 to a stop only after the latter has engaged the boss 37, the push rod 31 may be made ineffective by either removing the collar 32 entirely from the rod 31, or by raising the collar 32 to such an extent that it will not be engaged by the sleeve 34 during the upward or retraction stroke of the press ram.

The press platen 35 has connected thereto a punch 40 which, when subjected to hydraulic pressure and engaging the shaft to be straight-

ened, will exert a straightening force on said shaft.

The conduit 18 is also connected with the tank 15 by means of a conduit 41 (Figure 6) having a safety or pressure relief valve 42 therein so that if, for some reason, an undue pressure should develop in the conduit 18, this undue pressure may be relieved into the tank 15 through the relief valve 42. It is, of course, understood that the relief valve 42 is set for a pressure higher than the pressure required for causing the servomotor 39 to shift the pump 17 into neutral or no delivery position. A conduit 43 connects the tank 15 with the four-way valve 19.

Branching off from the conduit 21 is a conduit 44 comprising a check valve 45 and leading to a predetermined point in the wall of the press cylinder 14. It will be clear that, due to this arrangement, the ram 36 will move downwardly at a high speed from the position shown in Figure 6, until the piston portion 36' of the ram 36, during its downward movement, has moved beyond the connection of the press cylinder 14 with the conduit 44. This is due to the fact that during the first portion of the downward stroke of the ram 36, the fluid expelled by the piston portion 36' escapes through the check valve 45 and conduits 44 and 21 and, furthermore, through conduit 43 into the tank 15. However, as soon as the piston portion 36' has reached a position at which its upper surface is at a level lower than the inlet of the conduit 44 into the cylinder 14, the fluid expelled from the lower portion of the press cylinder 14 has to flow through the choke 24, which may be adjusted according to the rate at which the last end of the downward stroke of the ram 36 is desired to be performed.

Connected with the lower portion of the press cylinder 14 is a conduit 48 leading to a bellows switch of conventional structure, generally designated 49, which includes a bellows 50 having connected thereto a rod 51 and a contact or terminal 52. The bellows 50 houses a spring (not shown) which continuously urges the terminal or contact 52 away from the terminal or contact 53, while a predetermined pressure in conduit 48 is adapted to overcome the force of the said spring so as to bring the terminal 52 into engagement with the terminal 53, which latter is connected by line 54 with the main supply line 55.

The terminal 52 is connected by a line 56 with an electric motor 57. The electric motor 57 is furthermore connected with a line 58 adapted by closure of the switch 59 to be connected with the line 60 leading to the main supply line 61. Also connected to the main supply line 61 is a line 62 adapted, by closure of the switch 63, to be connected with the line 64 which, in its turn, is connected to the electric motor 57.

The electric motor 57 has connected to its shaft a sprocket wheel 65 which is drivingly connected by a sprocket chain 66 (Figures 1 and 2) with a sprocket wheel 67 which is keyed to a shaft 68. Also keyed to the shaft 68 is a pinion 69 meshing with a rack 70, which latter is connected to the press bed 71 in any convenient manner. The press bed 71 is preferably composed of a plurality of H-shaped members interconnected in any convenient manner. In this way, operation of the electric motor 57 is adapted to drive the pinion 69, thereby causing the carriage 72 to move along the bed 71 by means of

its rollers 73 rolling on the rails 74. The rails 74 are rigidly connected to the press bed in any convenient manner.

Slight movements of the carriage may also be effected manually by means of the hand wheel 75, which is keyed to a shaft 76 having rigidly connected thereto a clutch member 77. The shaft 76, together with the clutch member 77, is slidably supported so as to be moved inwardly, thereby causing the clutch member 77 to engage a correspondingly shaped clutch member 78 which, in its turn, is drivingly connected to a sprocket wheel 79. The sprocket wheel 79 is drivingly connected by means of a sprocket chain 80 with a sprocket wheel 81 which is keyed to the shaft 68.

Also connected with the main supply line 61 is a line 82 adapted, by closure of the switch 83, to be connected with a line 84, which comprises a solenoid 85 and leads to the line 56. The solenoid 85 controls an armature 86 which, in its turn, is connected to a valve member 87 of a four-way valve, generally designated 88 and having one port plugged so as to operate as a three-way valve. The valve 88 is of conventional design and causes interruption between the conduit 90 on one hand and the conduits 89 and 91 on the other hand when the solenoid 85 is deenergized. In this instance, the conduits 89 and 91 communicate with each other.

A spring 92 continuously urges the valve member 87 into its lower position for establishing fluid connection between the conduits 89 and 91, whereas energization of the solenoid 85 causes the valve member 87 to move into its upper position, thereby breaking the fluid connection between the conduits 89 and 91, while establishing fluid connection between the conduits 89 and 90.

Connected with the conduit 89 are two conduits 93 and 94 which respectively communicate through bores 95 and 96 in plungers 97 and 98 with cylinders 99 and 100. The cylinder-plunger arrangements 97, 99; 98, 100 serve respectively to actuate the supporting rollers 101 and 102. While only the structural details of the cylinder-plunger arrangement 97, 99 are shown in Figures 3 and 4, it is understood that the cylinder-plunger arrangement 98, 100 is similarly constructed.

Referring to Figures 3 and 4, the cylinder 99 forms a part of a slide 103 which is reciprocably mounted between flanges 104 of a slide 105 which is slidable on the press bed 71. To effect the sliding movement of the slide 105 relative to the press bed 71, the slide 105 carries a shaft 106 with a square head 107 adapted to be engaged by a corresponding wrench. The other end of the shaft 106 has keyed thereto a pinion 108 which meshes with a rack 109 connected to the press bed 71.

The plunger 97, cooperating with the cylinder 99, is stationarily mounted on the slide 105, and the connection 93, 89 with the valve 88 is flexible.

To limit the upward movement of the slide 103 relative to the slide 105, two bolts 110 are provided which are rigidly connected to the slide 105 and extend through bores in the slide 103 and have at their upper ends an abutment nut 111 and locking nut 112. The abutment nut 111, when engaging the slide 103, limits further upward movement thereof.

The slide 103 carries the two rollers 101 which are keyed to shafts 113 rotatably mounted in bearings 114. Keyed to the shafts 113 are pinions 115 which mesh with a pinion 116. The pinion 116 is rigidly connected to a sprocket wheel

117 which, in its turn, is drivingly connected to a sprocket wheel 118. The sprocket wheel 118 is keyed to a shaft 119 of a rotary fluid motor 120 which may be of any conventional design, and may be of the radial piston type or the radial vane type, if desired. Rotation of the motor 120 will cause rotation of the central pinion 116 meshing with the pinions 115, and thereby will cause the rollers 101 to rotate. While the rollers 101 are directly driven by a motor, namely the motor 120, the rollers 102 have not connected therewith such a drive but are rotated by the shaft to be straightened. In other words, when the shaft to be straightened is supported by the rollers 101, 102, rotation of the rollers 101 causes rotation of the shaft to be straightened and the latter, while rotating, also rotates the rollers 102.

The motor 120 is rigidly connected to a flange 121 forming a part of the slide 105. The motor 120 is connected by a conduit 122 with a valve 123, which is of the same type as the valve 88. The valve 123 has a valve member 124 with an armature 125 controlled by a solenoid 126. The solenoid 126 is mounted in a line 127, having one end connected to the line 56, while the other end is adapted, by closure of the switch 128, to be connected with a line 129 leading to the line 82.

The valve member 124 is continuously urged downwardly by a spring 130 so as to establish fluid connection between the conduit 122 and the conduit 131 leading to the tank 132. Energization of the solenoid 126 causes the valve member 124 to move upwardly so as to interrupt fluid connection between the conduits 122 and 131, while establishing fluid connection between the conduits 122 and 133, which latter comprises an adjustable choke 134 and communicates with the conduit 90 connected with the pressure side of the pump 135. The pump 135 may be of similar construction as the pump 17, and may also be provided with servomotor means 135' which, in response to a predetermined pressure in the conduit 90, shifts the pump 135 to substantially no delivery position. The suction side of the pump 135 is connected through conduit 136 with the tank 132.

The hydraulic motor 120 is furthermore connected through a conduit 137 with the conduit 131. Mounted in the conduit 90 between the pump 135 and the valve 88 is a check valve 138 adapted to allow fluid to pass from the pump 135 to the valve 88, while preventing the flow of fluid in the reverse direction.

Also slidably mounted on the press bed 71 are a pair of slides, generally designated 139 and 140, with supporting blocks 141 and 142. Since both slides 139 and 140 fully correspond in structure, only one slide, namely the slide 140, is shown in detail in Figure 5.

The supporting block 142 vertically slidably in the slide 140 is adjustable by means of a wedge 143 and a spindle 144, threadedly engaging the wedge 143. The ends of the spindle 144 are journaled in the slide 140. One end of the spindle 144 has keyed thereto a hand wheel 145 for rotating the spindle, while longitudinal movement of the spindle 144 in the slide 140 is prevented by the hub 146 of the hand wheel 145 and the collar 147 keyed to the spindle 144.

To hold the supporting block 142 and wedge 143 in proper alignment, the supporting block 142 is provided with a ridge or ledge 148 engaging a correspondingly shaped groove 149 in the wedge 143. The supporting block 141 is similarly adjustable by means of the hand wheel 150.

The slides 139 and 140 are movable on the bed 71 by simply pushing against the slides 139, 140. If desired, locking means of any conventional design may be provided for locking the slides 139, 140 on their proper places, although this is actually not necessary, since these slides are properly held in their respective places by the pressure exerted by the press ram 36.

Operation

It may be assumed that the valve 19 (Figures 2 and 6) is shifted into such a position that the pressure line 18 is connected with the line 21, while the conduit 20 is connected with the conduit 43. In this position, the fluid pressure conveyed through the conduit 21 beneath the piston portion 36' holds the ram 36 in its desired upper position.

It may furthermore be assumed that the cylinders 99 and 100, forming a part of the slides carrying the rollers 101, 102, are in their lowermost position, at which the effective supporting surfaces of the rollers 101, 102 are at a lower level than the effective supporting surfaces of the supporting blocks 141, 142.

If it is now desired to straighten a shaft on the press according to the invention, the operator first moves the slides 139, 140 toward or away from each other so that the distance between the slides will be somewhat shorter than the length of the shaft to be straightened. Thereupon, the operator moves the rollers 101, 102 into the neighborhood of the slides 139, 140 by rotating the shafts 103 and 106' respectively pertaining to the slides 105 and 105'. When the rollers 101 and 102 have been so positioned that they will be able, when lifted, to support the shaft to be straightened, the shaft to be straightened is placed on the blocks 141, 142. By rotation of the handwheels 145, 150, the blocks 142, 141 are so adjusted that the longitudinal axis of the shaft to be straightened is horizontal.

The operator now closes the switch 83, thereby establishing a circuit comprising the main supply line 61, lines 82 and 84, solenoid 85, line 56, terminals 52, 53, which at this time engage each other, line 54 and main supply line 55. As a result thereof, the solenoid 85 is energized and moves the valve member 87 upwardly so as to break fluid connection between the conduits 89 and 91, while establishing fluid connection between the conduits 90 and 89. Therefore, pressure fluid from the pump 135 passes through the conduits 90, 89, 93 and 94 into the cylinders 99 and 100, thereby lifting these cylinders and, consequently also the slides respectively carrying the rollers 101 and 102.

When, during the upward stroke of the cylinders 99, 100, the nuts 111 engage the bottom of the slides carrying the rollers 101, 102, the cylinders 99 and 100 come to a stop. At this time, the effective supporting surfaces of the rollers are higher than the effective supporting surfaces of the supporting blocks 141, 142, so that the rollers have lifted the shaft to be straightened off the supporting blocks and now support the said shaft. If the longitudinal axis of the shaft should not be horizontal, it is merely necessary to effect an adjustment of the nuts 111 to bring about movement of the shaft into the desired position.

When the shaft to be straightened is properly supported by the rollers 101, 102, the operator closes the switch 128, thereby closing a circuit comprising the main supply line 61, line 129, sole-

noid 126, line 127, lines 56 and 54 and the main supply line 55. As a result thereof, the solenoid 126 is energized and moves the valve member 124 into position for breaking fluid connection between the conduits 122 and 131, while establishing fluid connection between the conduits 122 and 133. Pressure fluid from the pump 135 now passes through conduits 133 and 122 into the fluid motor 120, which latter rotates the pinions 116 and 115 and, thereby, the rollers 101. The rollers 101 in their turn rotate the shaft to be straightened and the rollers 102.

The speed of rotation of the motor 120 and thereby the rollers supporting the shaft to be straightened, is controlled by the setting of the choke 134. While the shaft is now rotating, the operator, by means of any standard measuring gauges commonly used for detecting bends in a shaft, determines the portion or portions of the shaft to be straightened and marks the same accordingly.

After this step has been performed and when the shaft to be straightened has been moved by the rollers into the desired position, the rotation of the rollers and thereby of the shaft is stopped by stopping the motor 120. This is effected by opening the switch 128 so that the solenoid 126 becomes deenergized and the spring 130 moves the valve member 124 for breaking fluid connection between the conduits 122 and 133, while establishing fluid connection between the conduits 122 and 131. Thereupon, the operator opens the switch 83, thereby deenergizing the solenoid 85 and causing the spring 92 to move the valve member 87 downwardly so as to break fluid connection between the conduits 89 and 90, while establishing fluid connection between the conduits 89 and 91.

While the pump 135 will now move to its neutral or no delivery position, the weight of the shaft to be straightened causes the cylinders 99 and 100 to move downwardly. If desired, a choke, indicated in dot-dash lines and designated 151, may be provided in the conduit 91 for controlling the downward speed of the cylinders 99 and 100. The fluid expelled from the cylinders 99 and 100 during the downward movement of the rollers 101 and 102 passes through the bores 95 and 96 and the conduits 89 and 91 into the tank 132. When the rollers 101 and 102, during their downward movement, reach a position at which the effective supporting surfaces of the rollers are level with the effective supporting surfaces of the blocks 141, 142, the shaft to be straightened will automatically be transferred to these blocks and will then be solely supported by the latter. The cylinders 99 and 100 then move further downwardly by their own weight until the bottom of the slides, carrying the rollers, engages the bottom of the slides 105, 105'.

The operator now closes one of the switches 59 or 63, according to the desired direction of rotation of the electric motor 57. When the motor 57 thus rotates, also the sprocket wheels 65 and 67 will rotate in a corresponding direction and thereby cause the pinion 69, meshing with the rack 70, to move the carriage 72 and, consequently, also the press cylinder 14 carried thereby along the bed 71, in a corresponding direction. When the carriage 72 has reached such a position that the straightening punch 40 occupies a position in alignment with the portion to be straightened, the motor 57 is brought to a stop by opening the respective switch 59 or 63, 73 which has previously closed for energizing the

motor 57. All parts now occupy the position required for the actual straightening operation.

To carry out the straightening operation proper, the operator, by actuating the hand lever 27, moves the valve 19 into such a position that fluid connection is established between the conduits 18 and 20, while the conduit 21 is hydraulically connected to the conduit 43. As a result thereof, pressure fluid from the pump 17 passes through conduits 18 and 20 into the upper portion of the press cylinder 14 where it acts upon the ram 36 and moves the same downwardly, while the fluid expelled from the lower portion of the press cylinder 14 during this downward movement escapes through the check valve 45, conduits 44 and 43 into the tank 15. In this way, the ram 36 will perform a fast downward movement during the first portion of its downward stroke.

As soon as the piston portion 36' has closed the port 47, no more fluid can escape through the check valve 45, and all fluid expelled from the lower portion of the cylinder 14 now has to pass through the choke 24. According to the adjustment of the choke 24, the last portion of the downward stroke of the ram 36 will be effected at a more or less reduced speed. The downward movement of the ram 36 and the platen 35 with the punch 40 connected thereto causes the latter to exert a straightening force on the shaft to be straightened.

When the operator considers the stroke of the ram 36 to be sufficient so as to have performed the desired straightening effect, the valve 19 is reversed so that fluid connection is established between the conduits 18 and 21, while simultaneously the conduit 20 is connected with the conduit 43. As a result thereof, fluid delivered by the pump 17 passes through conduit 21 and check valve 22 into the lower portion of the press cylinder 14 and moves the ram 36 upwardly, while the fluid expelled from the upper portion of the cylinder 14 escapes through conduits 20 and 43 into the tank 15. The valve 23 may then, by energization of the solenoid 85, again be shifted into position for admitting pressure fluid to the cylinders 99 and 100 so that the rollers 101 and 102 again move upwardly. When, during this upward movement of the rollers 101 and 102, the effective supporting surfaces thereof reach the level of the respective supporting surfaces of the supporting blocks 141, 142, they take over the shaft to be straightened and, during further upward movement of the rollers, lift the said shaft off the supporting blocks 141 and 142.

The operator then checks the effect of the last mentioned straightening operation and, if desired, may repeat the straightening operation in the manner described above, or proceed to straighten another portion of the shaft.

When the ram 36 has been fully retracted so as to engage the boss 37, the ram 36 stops and when a predetermined pressure has developed in the lower part of the press cylinder 14, this pressure conveyed through conduit 18 to the servomotor 39 causes the latter to shift the pump 17 to substantially neutral or no delivery position.

The contact or terminal 52, which is adjustably mounted on the rod 51, is so adjusted that when the ram 36 has reached its desired retracted position, the terminal 52 engages the terminal 53, thereby electrically interconnecting the lines 54 and 56.

In the description of the operation as set forth above, it was assumed that the ram 36 returns to its uppermost position, as shown in Figure 6. In this instance, the push rod 31 is made in-

5 effective by adjusting the collar 32 so that it will not be engaged by the sleeve 34 (Figure 2). However, if it is desired not to fully retract the ram 36 during its upward movement, the collar 32 is so adjusted that, at a desired point of 10 travel of the retraction stroke of the ram 36, the collar 32 will be engaged by the sleeve 34, thereby lifting the push rod 31 and causing the latter, by means of the lever arm 28, to shift the valve 19 to an intermediate or neutral position in which 15 the flow of fluid to and from the cylinder 14 is blocked. This causes the ram 36 to stop during its upward movement at a desired point prior to the engagement of the boss 37 by the piston portion 36'. It is, of course, understood that the 20 terminal 52 will, in this instance, likewise be adjusted so that when the ram 36, at the end of its upward movement, comes to a standstill, the contact 52 again engages the contact 53.

The adjustment of the contact 52 in such a 25 manner that the latter engages the contact 53 at the end of the retraction stroke of the ram 36 constitutes a safeguard against accidental premature lifting of the work piece by the rollers 101, 102 from the supporting blocks 141, 142 before the ram 36 has been retracted to a desired 30 position.

It will be clear that the valve member 87 cannot be shifted into position for lifting the cylinders 99 and 100, and thereby the rollers 101, 35 102, as long as the electric connection between the lines 54 and 56 is interrupted, due to the spacing between the contacts 52 and 53. On the other hand, as mentioned above, these contacts will engage each other only when the ram 36 40 has been returned to its desired retracted position.

It will furthermore be noted that if it should accidentally be forgotten to open the switch 83 for lowering the cylinders 99 and 100 and thereby 45 the rollers 101 and 102, while the valve 19 has been shifted for downward movement of the ram 36, the energizing circuit for the solenoid 85 will automatically be broken. This is due to the fact that the shifting of the valve 19 into downward 50 position of the ram 36, establishes fluid connection between the lower portion of the cylinder 14 and the tank 15, and that, due to this pressure drop in the cylinder 14, the spring in the bellows switch 49 causes disengagement of the 55 contacts 52 and 53. Consequently, even if the downward movement of the ram 36 should be started before the operator has opened the switch 83, the work piece will automatically be transferred from the rollers 101, 102 to the supporting blocks 141, 142.

While thus far the rollers 101, 102 have been described as hydraulically movable in vertical direction, whereas the supporting blocks 141, 142 have been described as mechanically adjustable 65 in vertical direction, it is to be understood that although this arrangement is preferable, it does not constitute the only way of carrying out the present invention. For instance, if desired, the arrangement may be such that the rollers are 70 adjustable in vertical direction by mechanical means, whereas the supporting blocks are movable in vertical direction by hydraulic means. In other words, the reverse arrangement, described above in detail, may be adopted. In this instance, the hydraulic system of Figure 6 will be 75

exactly the same, and the only difference will consist in that the cylinders 99 and 100, instead of carrying and actuating the rollers 101 and 102, will carry and actuate the blocks 141, 142. Figure 7 shows the block of Figure 5 carried by the cylinder 99, whereas Figure 8 shows the rollers 101 adjustable mechanically.

With such an arrangement, the effective supporting surfaces of the rollers will normally be at a level higher than the effective supporting surfaces of the supporting blocks and, when the checking operation has been effected, pressure fluid supplied to the cylinders 99 and 100 will lift the blocks so that they take over the shaft to be straightened from the rollers into the desired height.

To hold the shaft at the desired height, the valve 89 would be shifted into an intermediate or neutral position, in which any flow of fluid therethrough is blocked, so that the fluid in the cylinders 99 and 100 is completely entrapped. In all other respects, this arrangement will correspond to the arrangement described above in detail.

If the straightening press is to be used mostly for straightening a specific type of shafts, for instance, shafts of equal diameter only, or shafts of the same taper, no adjustment of the supporting blocks is necessary, so that the adjusting means shown in Figure 5 in detail for the adjusting of the supporting blocks may be omitted. The supporting blocks may then be arranged so that they can be replaced by other supporting blocks. Similarly, if the supporting blocks are hydraulically moved in vertical direction, the mechanical adjusting means for the rollers may be omitted when the press is used mostly for straightening one and the same type of shafts.

It will be understood that I desire to comprehend within my invention such modifications as come within the scope of the claims and the invention.

Having thus fully described my invention, what I claim as new and desire to secure by Letters Patent is:

1. In a shaft straightening press, a bed, first supporting means on said bed for receiving and supporting a shaft to be straightened prior to the actual straightening operation, second supporting means mounted on said bed for supporting said shaft during the actual straightening operation, fluid operable means for selectively transferring said shaft from said first supporting means to said second supporting means or vice versa, valve means hydraulically connected with said fluid operable means for controlling the flow of fluid to and from said fluid operable means, electric control means for controlling said valve means, a press ram for exerting straightening pressure on said shaft while it is being supported by said second supporting means, said press ram having associated therewith fluid operable advancing and retracting means for reciprocating said ram, and electric switch means operatively connected with said retracting means for controlling said electric control means.

2. In a shaft straightening press, a bed, a plurality of spaced first supporting units mounted on said bed for supporting a shaft to be straightened prior to the actual straightening operation and for allowing checking of the shaft portion or portions to be straightened, a plurality of spaced second supporting units mounted on said bed for supporting said shaft during the actual straightening operation, fluid operable means for

selectively transferring said shaft from said first supporting units to said second supporting units or vice versa, first adjusting means associated with said first units for individually varying the maximum stroke thereof, second adjusting means associated with said second units and operable individually for adjusting the respective second units, and means for exerting straightening pressure on said shaft while it is being supported by said second supporting units.

3. In a shaft straightening press, a bed, a plurality of spaced first supporting units on said bed for supporting a shaft and allowing checking thereof as to its contour, a plurality of spaced second supporting units on said bed for supporting a shaft to be straightened during the actual straightening operation, means associated with said first supporting units and operable to move said first supporting units relative to each other, means associated with said second supporting units for moving the same relative to each other, fluid operable means for selectively transferring said shaft from said first supporting units to said second supporting units or vice versa, and means for exerting straightening pressure on said shaft while it is being supported by said second supporting units.

4. In a shaft straightening press, a bed, spaced pairs of rollers on said bed for receiving a shaft to be straightened and allowing checking of said shaft as to its contour, supporting means mounted on said bed for supporting the shaft to be straightened during the actual straightening operation, the effective supporting surfaces of said supporting means being normally at a higher level than the effective supporting surfaces of said roller pairs, fluid operable means for actuating said roller pairs so as selectively to lift the effective supporting surfaces thereof to a level higher than the level of said supporting means for transferring said shaft from said supporting means to said roller pairs, or to allow movement of the effective supporting surfaces of the said roller pairs to a level lower than the effective supporting surfaces of said supporting means for transferring the shaft to be straightened from said roller pairs to said supporting means, fluid flow restricting means associated with said fluid operable means and operable to vary the rate of transfer of the shaft to be straightened from said roller pairs to said supporting means, and means for exerting straightening pressure on the shaft to be straightened when the latter is being supported by said supporting means.

5. In a shaft straightening press, a bed, first supporting means on said bed for receiving a shaft to be straightened and allowing checking thereof as to its contour, second supporting means mounted on said bed for supporting the shaft to be straightened during the actual straightening operation, fluid operable means for selectively transferring said shaft from said first supporting means to said second supporting means or vice versa, hydraulic motor means including a reciprocable straightening punch operable to exert straightening pressure on the shaft to be straightened while it is being supported by said second supporting means, and means associated with said motor means and operable automatically in response to the initiation of a working stroke of said straightening punch to cause transfer of the shaft to be straightened from said first supporting means to said second supporting means if said transfer had not been effected prior to said initiation of said working stroke.

6. In a shaft straightening press, a bed, spaced roller units on said bed for receiving a shaft to be straightened and allowing checking of said shaft as to its contour, fluid operable motor means associated with at least one of said roller units for rotating said shaft when it is being supported by said roller units, spaced individually adjustable supporting means for supporting the shaft to be straightened during the actual straightening operation, a fluid operable cylinder-piston-assembly associated with each of said roller units and operable selectively to lower the shaft to be straightened from said roller units upon said supporting means, or to cause said roller units to pick up said shaft from said supporting means, adjusting means associated with each of said roller units for individually adjusting and limiting the maximum stroke of each roller unit, to thereby accommodate shafts of irregular shape, and means for exerting straightening pressure on said shaft while it is being supported by said supporting means.

7. In a shaft straightening press, a bed, spaced roller means on said bed for receiving a shaft to be straightened and allowing checking of said shaft as to its contour, fluid operable motor means associated with at least some of said roller means for rotating said shaft when it is being supported by said roller means, spaced supporting members for supporting the shaft to be straightened during the actual straightening operation, a fluid operable cylinder-piston-assembly associated with said supporting members and operable selectively to pick up the shaft to be straightened from said roller means or to lower said shaft from said supporting members upon said roller means, and means for exerting straightening pressure on the shaft to be straightened while it is being supported by said supporting members.

8. In a shaft straightening press, a bed, spaced roller means on said bed for receiving a shaft to be straightened and allowing checking of said shaft as to its contour, fluid operable motor means associated with at least some of said roller means for rotating said shaft when it is being supported by said roller means, spaced supporting means for supporting the shaft to be straightened during the actual straightening operation, a fluid operable cylinder-piston-assembly associated with said roller means and operable selectively to lower the shaft to be straightened from said roller means upon said supporting means, or to cause said roller means to pick up said shaft from said supporting means, straightening means movable to exert straightening pressure on the shaft to be straightened while it is being supported by said supporting means, and means for preventing said roller means for picking up said shaft from said supporting means prior to the movement of said straightening means into a predetermined position.

9. In a shaft straightening press, a bed, spaced roller means on said bed for receiving a shaft to be straightened and allowing checking of said shaft as to its contour, spaced supporting members for supporting the shaft to be straightened during the actual straightening operation, a fluid operable cylinder-piston-assembly associated with said roller means and operable selectively to transfer said shaft from said roller means to said supporting members or vice versa, fluid operable straightening means for exerting straightening pressure on said shaft while it is being supported by said supporting members, motor

means for moving said straightening means along said bed, and valve means hydraulically connected with said fluid operable cylinder-piston-assembly for controlling the rate of transfer of the shaft to be straightened from said roller means to said supporting members.

10. In a shaft straightening press, a bed, spaced roller means on said bed for receiving a shaft to be straightened and allowing checking thereof as to its contour, spaced supporting members for supporting the shaft to be straightened during the actual straightening operation, a fluid operable cylinder-piston-assembly associated with said roller means for selectively transferring said shaft from said roller means to said supporting members or vice versa, fluid operable straightening means for exerting straightening pressure on said shaft while it is being supported by said supporting members, fluid operable motor means associated with said roller means for rotating said roller means, a first fluid source for supplying pressure fluid to said cylinder-piston-assembly and said fluid operable motor means, and a separate fluid source for supplying pressure fluid to said fluid operable straightening means to actuate the same.

11. In a shaft straightening press, a bed, spaced roller means on said bed for receiving a shaft to be straightened and allowing checking thereof as to its contour, each of said roller means having associated therewith a fluid operable cylinder-piston-assembly for substantially vertically moving said roller means, adjusting means associated with each of said roller means for varying the maximum stroke of the respective roller means, spaced supporting means for supporting said shaft during the actual straightening operation, said cylinder-piston-assemblies being adapted to move said roller means relative to said supporting means for selectively transferring a shaft to be straightened from said roller means to said supporting means or vice versa, and straightening means operable to exert straightening pressure on said shaft while it is being supported by said supporting means.

12. In a shaft straightening press, a bed, spaced roller means on said bed for receiving a shaft to be straightened and allowing checking thereof as to its contour, actuating means for moving said roller means in substantially vertical direction, a plurality of spaced supporting members for supporting a shaft to be straightened during the actual straightening operation, each of said supporting members having associated therewith adjusting means for substantially vertically adjusting said supporting members, means associated with said roller means for varying the maximum stroke thereof, fluid operable means for exerting relative movement of said roller means and said supporting members to transfer a shaft to be straightened from said roller means to said supporting members or vice versa, and straightening means operable to exert straightening pressure on said shaft while it is being supported by said supporting members.

13. In a shaft straightening press, a bed, spaced roller means on said bed for receiving a shaft to be straightened and allowing checking thereof as to its contour, a plurality of spaced supporting members for supporting a shaft to be straightened during the actual straightening operation, each of said roller means having associated therewith a fluid operable cylinder-piston-assembly for substantially vertically moving said

roller means, adjusting means associated with each of said roller means for varying the maximum stroke thereof, said cylinder-piston-assemblies being adapted to lift the effective supporting surfaces of said roller means to a level higher than the level of the effective supporting surfaces of said supporting members, and means for exerting straightening pressure on the shaft to be straightened while the latter is being supported by said supporting members.

14. In a shaft straightening press, a bed, first supporting means on said bed for receiving a shaft to be straightened and allowing checking thereof as to its contour, second supporting means mounted on said bed for supporting said shaft during the actual straightening operation, fluid operable means for moving said supporting means in substantially vertical direction relative to each other for selectively transferring the shaft to be straightened from said first supporting means to said second supporting means or vice versa, a press ram having associated therewith fluid operable advancing and retracting means for reciprocating said ram and causing the same selectively to exert straightening pressure on the shaft to be straightened while it is being supported by said last mentioned supporting means, and means associated with said retracting means and operable, in response to a predetermined low pressure acting on said retracting means, automatically to bring about transfer of the shaft to be straightened from said first supporting means to said second supporting means..

15. In a shaft straightening press, a bed, first supporting means on said bed for receiving and supporting a shaft to be straightened prior to the actual straightening operation, second supporting means mounted on said bed for supporting said shaft during the actual straightening operation, fluid operable means for selectively transferring said shaft from said first supporting means to said second supporting means or vice versa,

straightening means for exerting straightening pressure on said shaft while it is being supported by said second supporting means, and means preventing said shaft from being transferred from said second supporting means to said first supporting means prior to the movement of said straightening means into a predetermined position.

16. In a shaft straightening press, a bed, first supporting means on said bed for receiving and supporting a shaft to be straightened prior to the actual straightening operation, second supporting means mounted on said bed for supporting said shaft during the actual straightening operation, fluid operable means for selectively transferring said shaft from said first supporting means to said second supporting means or vice versa, straightening means for exerting straightening pressure on said shaft while it is supported by said second supporting means, and means responsive to the initiation of a straightening stroke of said straightening means for automatically transferring the shaft to be straightened from said first supporting means to said second supporting means.

17. In a shaft straightening press, a bed, roller means on said bed for receiving and supporting a shaft to be straightened prior to the actual straightening operation, supporting means mounted on said bed for supporting said shaft during the actual straightening operation, fluid operable means for selectively transferring said shaft from said roller means to said supporting means or vice versa, fluid operable motor means for rotating said roller means, means hydraulically connected with said motor means and operable to control the speed of said fluid operable motor means and thereby also the speed of rotation of said roller means, and means for exerting straightening pressure on said shaft while it is being supported by said supporting means.

WALTER ERNST.
